(57) CLAIM

The ornamental design for a dispenser, as shown and described.

DESCRIPTION

FIG. 1 is a perspective view of a dispenser showing the new design.

FIG. 2 is a front elevation view of the dispenser shown in FIG. 1;

FIG. 3 is a top plan view of the dispenser shown in FIG. 1;

FIG. 4 is a right-side elevation view of the dispenser shown in FIG. 1;

FIG. 5 is a left-side elevation view of the dispenser shown in FIG. 1;

FIG. 6 is a bottom plan view of the dispenser shown in FIG. 1; and,

FIG. 7 is a rear elevation view of the dispenser shown in FIG. 1.

The portions shown in broken lines do not form part of the claimed design. The separation is used to indicate that, for ease of illustration, the precise length of the dispenser is not claimed.
